Sydney Prescott
ATTORNEY

UNITED STATES PATENT OFFICE.

RUPERT E. RUNDELL, OF BROOKLYN, NEW YORK, ASSIGNOR TO INTERNATIONAL CIGAR MACHINERY COMPANY, A CORPORATION OF NEW JERSEY.

CIGAR-BUNCH-FILLER FEED.

Application filed September 13, 1923. Serial No. 662,455.

To all whom it may concern:

Be it known that I, RUPERT E. RUNDELL, a citizen of the United States, residing at Brooklyn, county of Kings, and State of New York, have invented a new and useful Improvement in Cigar-Bunch-Filler Feeds, of which the following is a specification.

This invention relates to an improved cigar bunch filler feed. In making long 10 filler cigar bunches by machinery, it is customary to spread the tobacco for the filler on a feed belt which advances the filler in sheet form to a device which severs individual charges from the sheet of filler so that 15 they may be successively enclosed and rolled in a binder to form a cigar bunch. Cigar bunches vary widely in form, and in making certain forms of cigar bunches it has been found desirable to accelerate the movement 20 of predetermined parts of the filler in order to provide for more filler in corresponding parts of the bunch undergoing formation. The main object of the present invention is the production of a device for 25 accomplishing this result. Another object of the invention is the production of a device of this general character which may be used in connection with existing machines. With these and other objects not specifically 30 mentioned in view, the invention consists in certain constructions and combinations which will be hereinafter fully described and then specifically set forth in the claims hereunto appended.

35 In the accompanying drawings, which form a part of this specification and in which like characters of reference indicate the same or like parts, Fig. 1 is a longitudinal central sectional view of a device constructed in accordance with the invention; and Fig. 2 is a front elevation of the structure shown in Fig. 1, partly broken away.

40 In carrying the invention into effect, there is provided means for advancing all parts of a sheet of filler at uniform speed, as is customary in cigar machines, and means receiving filler therefrom and accelerating the movement of predetermined parts of said filler in order to provide more filler in the corresponding parts of the bunches undergoing formation. In the best constructions, a belt of the usual type is used for advancing the sheet of filler to a receiving support coacting with which is a plurality of feed-

ing devices for advancing filler along said support, said feeding devices being yieldingly driven at different speeds. The parts and devices referred to may be widely varied in construction within the scope of the 60 claims for the particular device selected to illustrate the invention is but one of many possible concrete embodiments of the same, and the invention therefore is not to be restricted to the precise details of the structure shown and described.

Referring to the drawings, 3 is a feed table of the construction usual in cigar making machines. Overlying the table 3 is a feed belt 4 also of the usual construction. 70 This feed belt runs over an idle pulley 5 rotating on a bar 6 supported by the side frame 7 of the cigar machine in connection with which the device is used. The belt 4 is driven by means not shown but well known in the cigar machine art. The belt functions to advance all parts of the sheets of filler at uniform speed. It will be understood that the tobacco is spread upon the belt by the feeding operator in the customary manner. The belt 4 advances the sheet of filler to a support 8 located just beyond the idle pulley 5, and at the far end of the support 8 there is provided a knife 9 the function of which is to sever individual charges from the advancing sheet of filler. The knife 9 is operated intermittently by mechanism not shown but well known in the art.

90 For the purpose of accelerating the movement of predetermined parts of the filler in order to advance more filler to corresponding parts of the charge to be severed by the knife 9, the following mechanism is provided. High above the feed belt 4 there is 95 provided a drive shaft 10 extending across the machine and journaled in brackets 11, 12 and 13 rising from the main frame of the cigar machine in connection with which the device is used. This drive shaft carries 100 at one end a sprocket 14 over which runs a driving shaft 15 deriving its motion from one of the shafts of the cigar machine not shown. Between the bearings 12 and 13, the shaft 10 is provided with a series of collars 16 splined thereto, and between each pair of collars is loosely mounted one of a series of driving gears 17 of different diameters. This series of driving gears meshes with a series of driven gears 18, also of different diameters and 105 110

loosely mounted on a bar 19 extending across the device and supported in bosses 20-20. Each driven gear 18 carries a sprocket 21 which is keyed thereto. Overrunning the 5 series of sprockets 21 is a series of chains 22 which also overrun idle sprockets 23 loosely mounted on a bar 24 extending across the device.

For the purpose of causing the series of 10 driving gears 17 to yieldingly operate the series of chains 22, there is provided a spring 25 coiled around the drive shaft 10. One end of this spring lies in a pocket formed in the bearing 13 and thrusts against the end 15 wall of said pocket. The other end of the spring bears against the adjacent collar 16. It will be remembered that all of the collars 16 are splined to the driving shaft and rotate with it. They are, however, free to 20 move longitudinally on the splines. The action of the spring 25, therefore, is to exert pressure longitudinally against the first collar 16, which in turn presses against the first driving gear 17, which in its turn presses 25 against the second collar 16, and so on down the line until the last collar 16 presses against the unyielding bearing 12. By means of this construction, all of the 30 driving gears are frictionally driven and drive the chains 22 at varying speeds. The chains and driving gears therefor are arranged in accordance with the contour of the bunch charge which it is desired to form and the faster running chains will of course, 35 wherever they may be in the series, accelerate the movement of the filler at that point. By rearrangement of the parts of this mechanism, therefore, cigar bunches of varying contour may be made on the same machine.

40 What is claimed is:

1. In a cigar bunch filler feed, the combination with means for advancing all parts of a sheet of filler at uniform speed, of means receiving said sheet of filler therefrom and 45 accelerating the movement of predetermined parts thereof.

2. In a cigar bunch filler feed, the combination with a belt for advancing all parts of a sheet of filler at uniform speed, of a support receiving the sheet of filler from said belt, a plurality of feeding devices for advancing filler along said support, and means for driving said devices at different speeds.

50 3. In a cigar bunch filler feed, the combination with a filler support, of a plurality of feeding devices for advancing filler along said support, a common driver, and connec-

tions between said driver and said devices for independently and yieldingly driving the latter.

55 4. In a cigar bunch filler feed, the combination with a filler support, of a plurality of feeding chains for advancing filler along said support, a common driver, and connections between said driver and said chains for independently and yieldingly driving the latter.

60 5. In a cigar bunch filler feed, the combination with a filler support, of a plurality of feeding chains for advancing filler along said support, a series of sprockets carrying said chains, a common driver, and friction gearing connecting said driver and said sprockets.

65 75 6. In a cigar bunch filler feed, the combination with a filler support, of a plurality of feeding chains for advancing filler along said support, a series of sprockets carrying said chains, a series of gears carried by said sprockets, a drive shaft, a series of collars 80 splined on said shaft, a series of driving gears loosely mounted on said shaft one between each pair of collars, and means acting to establish frictional contact of said collars and said driving gears.

85 90 7. In a cigar bunch filler feed, the combination with a filler support, of a plurality of feeding chains for advancing filler along said support, a series of sprockets carrying said chains, a series of gears of different diameters carried by said sprockets, a drive shaft, a series of collars splined on said shaft, a series of driving gears of different diameters loosely mounted on said shaft one 95 between each pair of collars, and a spring acting to establish frictional contact of said collars and said driving gears.

100 105 8. In a cigar bunch filler feed, the combination with a feed belt, of a filler support receiving filler from said belt, a plurality of feeding chains for advancing filler along said support, a series of sprockets carrying said chains, a series of gears of different diameters carried by said sprockets, a drive shaft, a series of collars splined on said shaft, a series of driving gears of different diameters loosely mounted on said shaft one between each pair of collars, and a spring acting to establish frictional contact of said collars and said driving gears.

110 In testimony whereof, I have signed my name to this specification.

RUPERT E. RUNDELL.
